UNITED STATES PATENT OFFICE.

ALBERT B. COBB, OF BOSTON, MASSACHUSETTS, ASSIGNOR TO COBB ELECTRIC APPLIANCE COMPANY, OF BOSTON, MASSACHUSETTS, A CORPORATION OF MASSACHUSETTS.

PRESSURE-OPERATED SWITCH.

1,406,613.

Specification of Letters Patent. Patented Feb. 14, 1922.

Application filed November 23, 1917. Serial No. 203,615.

To all whom it may concern:

Be it known that I, ALBERT B. COBB, a citizen of the United States, residing at Boston, in the county of Suffolk and State of 5 Massachusetts, have invented new and useful Improvements in Pressure-Operated Switches, of which the following is a specification.

The object of the present invention is to 10 provide a switch for opening and closing an electric heating circuit, said switch being controlled by the pressure of steam or other vapor generated by the heater whereof the circuit is thus controlled. A further object 15 is to provide means by which such a switch will remain closed as long as the pressure referred to is less than a certain predetermined maximum, and will be opened whenever the pressure reaches or exceeds this 20 maximum; and to enable adjustments to be made for causing the switch to be opened and closed at various degrees of pressure, without increasing the liability of the switch contacts to fuse together. A further object 25 is to provide a safety means by which to short circuit the heating circuit, or otherwise effect a complete cutting out of the heater or heating means, in case the switch contacts should fail to separate at the given condition 30 of pressure. The means by which these objects are accomplished, and the principles fundamental thereto are set forth in the following specification, in connection with one embodiment of such means, and are recited 35 in the appended claims.

In the drawing,

Figure 1 is a front elevation of a pressure gage having my improvement applied thereto, the same being represented with the dial 40 and pointer removed in order to show more clearly the parts wherein the invention is particularly comprised.

Figure 2 is a sectional view enlarged of one of the switch contacts and its holder.

45 Figure 3 is a sectional view enlarged of the complementary switch contact and the holder thereof.

Figure 4 is a diagram illustrating the electrical connections.

50 The same reference characters indicate the same parts in all the figures.

Referring to the drawing, 6 represents the case enclosing switch and 7 represents a pressure measuring element, here shown as a 55 curved spring tube of flattened cross section,

constituting the common Bourdon spring generally used in pressure gages to operate the indicating pointer. A link 8 is pivoted to the free end of the spring tube upon a finger 9 of the latter and is pivoted at its 60 other end to an arm 10 on a gear segment 11 which actuates the indicating hand or pointer. It may be assumed without special description that such segment actuates any of the mechanisms commonly used in pressure gages to move an indicating hand or pointer conformably to the pressure impelling the spring, or that the pressure-measuring element is coupled by any other operative means to accomplish the same end. 70

The pivot pin 12 between the link 8 and arm 10 projects forward and underlies an arm 13 carried by a plunger or slide 14 which is confined and is movable endwise in a guide 15 which is supported in any suitable 75 manner on a convenient part of the case or the frame which holds the transmission mechanism. This guide is here shown (Figure 2) as a cylinder open at one end in which the slide 14 fits, and having an orifice in the 80 other end through which the shank 16 of the slide passes, said orifice being surrounded by an abutment shoulder 17 between which and the plunger 14 is confined a spring 18. The arm 13 projects laterally through a slot 85 20 in the side of the guide, whereby a certain amount of endwise movement of the slide is permitted. This slide or plunger carries a switch contact 21.

The complementary contact is shown at 22 90 adjacent to the contact 21 and in the line of movement thereof. Contact 22 is mounted on a plug having a shank 23 which enters the bore of a tubular screw 24 which passes through the side of the case without touching it and is threaded adjustably through a conducting block 25 which is mounted on the inside of the case upon the lateral wall thereof. The plug 23 is movable endwise with respect to the screw 24, but is yieldingly 95 held therein, and preserved in electrical contact therewith, by a wire 26 one end of which is secured to the plug and the other end to the screw, both points of connection being electrically conductive, being secured by 100 solder or otherwise. This wire is coiled through part of its length so as to permit its extension and also to cause it to act as a spring yieldingly holding the plug 23 in the screw. 105 110

Both the conducting block 25 and the guide 15 are insulated from the case, by proper insulating material which is interposed between the parts thereof by which they are attached to the case, and the portions of the case on which they are respectively mounted.

A pin or stud 27 is mounted on the back of the case and passes through the same, but 10 is insulated electrically therefrom. It is connected with a suitable binding post on the gage back. Other binding posts 28 and 29 pass through the gage back and are insulated therefrom. All these posts are 15 equipped with means in rear of the gage for connecting wires thereto in the usual manner or other proper way. The post 28 is connected by a wire 30 with the block 25, and through the latter and screw 24, wire 26, 20 and plug 23 with the contact 22. A wire 31 passes from the binding post 29 to the shank 16 of the slide which carries the contact 21, and is thereby connected with the latter.

The diagram in Figure 4 shows the manner in which the contacts 21, 22, and 27 are coupled in circuit. In this diagram *a* and *b* are the line wires carrying the current supply. *c* represents a heating coil. One terminal of this coil is connected by wire 30 *d* with the contact 22, while the complementary contact 21 is connected by a wire *e* with one of the line wires. The third contact 27 is interposed in the run from the line wire *a* to the other terminal of the heating coil, 35 this run being represented by the wires *f* and *g*.

It will now be seen that when the contacts 21 and 22 are brought together the break represented by the dotted line *h* is closed, 40 whereby current may flow from the line through the heating coil, and back; but when the arm 13, which is joined to the contact 21 touches the contact 27, the gap represented by the broken line *k* is closed. Thereby a 45 short circuit between the line wires is established, which results in blowing out a fuse, or otherwise putting the line out of action.

The operation of the apparatus is as follows. When the pressure is at the lowest 50 degree, the Bourdon spring contracts to the smallest radius and the pin 12 is moved so as to allow the contact 21, impelled by the spring 18, and by gravity also when the gage 55 is set in an upright position, to touch contact 22. This contact is maintained as long as the pressure is below the given point at which the circuit is to be broken. When the pressure rises, pin 12 is moved and ultimately engages and lifts the arm 13, thereby separating the contact 21 from 22. If 60 these contacts should become fused together, or in other words and using the common term of the practical art, if the contacts 65 should "freeze," they will fail to separate,

but by reason of the loose mounting of the plug 23, the latter is able to follow the movement of the receding contact 21 until the arm 13 strikes the contact 27 and establishes the short circuit which puts the entire line 70 out of action. That is, contact 22 is mounted movably so that accidental "freezing" will not prevent the free distortion of the spring tube, but will permit the latter to move as designed, with results as described. 75 The wire 26 establishes a good and sufficient connection of the contact 22 in the circuit, and its spring construction holds the contact back when the switch is opened in the normal manner.

The foregoing description is made with reference to the particular form of the invention here illustrated, and is not intended to limit my protection otherwise than as appears from the express terms of the appended claims. The fundamental principles may be embodied in various modes of mounting and adjusting the switch contacts and various modes of mounting the relatively stationary contact to travel with the 90 relatively movable contact in case the two should become fused together, to accomplish the results herein described, all within the scope of the claims.

Although certain of my claims point out 95 the safety feature of means for establishing a short circuit in case the contacts should fuse together, other claims omit this feature because it is an emergency measure and in the normal operation of the switch does not 100 come into action. The characteristics of the switch contacts and of the manner in which they are mounted and adjusted enable them to carry heavy currents for long periods of time in any position which they 105 may occupy within their range of adjustment, without being heated to the temperature at which fusion will occur, or even to a degree high enough to injure them. Pointing out these characteristics with reference to the embodiment shown in the drawings, it will be noted that the contacts have contact faces of substantial width and area which are perpendicular to the line in which the relatively movable contact is 110 guided and likewise to the line or direction in which the normally stationary contact is shifted for adjustment, these two lines coinciding with one another. In other words the said contact or bearing surfaces 115 remain exactly parallel to one another in any position which the contacts may occupy within their range of adjustment. When the relatively movable contact is withdrawn from the other, all points in its contacting 120 face are removed equally at the same time from the contiguous points on the face of the other contact; and there is no reduction in the area of contact when adjustment of the 125 normally stationary contact member is made, 130

such as would occur if the contact members moved at such a time in divergent paths. Thus danger is avoided of development of high heat at the contact point, which would 5 occur if the bearing area should be materially diminished. There is also entire absence of sliding motion between the contacts in opening and closing, and thus absence of any friction which might tend to cause 10 resistance to the movement of the Bourdon spring.

Another useful characteristic of the switch is its compactness whereby it is enclosed within and protected by a cylindrical casing 15 no larger than is necessary for the protection of the Bourdon spring. This quality is achieved by arranging the holder or guide 15 so that the directions in which it constrains the movable contact to travel are 20 generally coincident with the directions in which the free end of the Bourdon spring moves by pressure actuation, and by locating this holder largely within the continuation of the curve of the spring tube. By the last 25 statement I do not mean that the holder is necessarily in the same plane or zone with the spring tube, but merely that it is substantially within an imaginary cylindrical surface projecting axially from the spring. 30 The mounting of the normally stationary contact is arranged to suit the location of the relatively movable contact, and to permit the inclusion of its contacting end within the case, its adjustment in the line of movement 35 of the movable contact, and accessibility for being adjusted from outside the case.

The Bourdon spring may be taken as typical of any pressure measuring or resisting element which is distorted or otherwise 40 moved when subjected to pressures of changing intensity, and is adapted in thus moving to operate one or the other of the members of a switch. Since the pressure which controls the Bourdon spring is a function of 45 the temperature developed in the heated fluid which actuates the spring, this spring may be considered as indirectly a temperature-controlled element.

What I claim and desire to secure by Letters Patent is:

1. A switch comprising the combination with a member movable in consequence of temperature changes, of complementary switch contacts, a tubular guide holding and 55 making electrical connection with one of said contacts constructed to permit movement of such contact toward and away from the other contact, a fixed support for said other contact in which the same is adjustably mounted with provision for adjustment in the same general direction as the movement of the first contact, said contacts being normally in engagement to close the 60 electrical circuit in which they are a part, and means by which the aforesaid member

when moved by temperature increase causes the first-named contact to be displaced from the last named contact.

2. An electrical switch comprising, in combination, a casing, an elongated curved member anchored at one end in said casing and capable of moving at its other end, said member being so movable in consequence of temperature changes, a holder mounted upon said casing, a contact piece supported by 75 said holder and constrained thereby to move in a given path which extends in the same general direction as the path wherein the free end of said curved member moves, a complementary contact mounted in a normally 80 stationary manner upon a part of said casing in a position where the first named contact may move into and out of contact with it; said contacts remaining normally in contact with one another when the temperature is 85 below the point at which the switch is designed to be opened, and inter-engageable projections connected with the curved member and the first-named contact arranged to engage and cause separation of said contact 90 from the second-named contact with movement of the curved member due to temperature rise above such point.

3. An electrical switch comprising in combination a casing, a curved spring tube flattened in cross section anchored at one end in said casing and there having an inlet for fluid and capable of moving at its other end, said tube being so movable in consequence of changes in the pressure of said fluid, a 100 holder mounted within said casing, a contact piece supported by said holder and constrained thereby to move in a given path, a complementary contact mounted in a normally stationary manner in a part of said casing in a position where the first named contact may move into and out of contact with it, and connections by which the pressure induced movement of said curved tube in consequence of increasing temperature 110 causes the separation of the first contact from the second contact, said connections being constructed to permit movement of the spring tube in consequence of diminishing pressure after the contacts have come 115 together and independently of the movable contact, the normally stationary contact being adjustable approximately in the path of the first-named contact whereby to cause opening of the switch by the before-mentioned separation of the contacts at different temperatures.

4. A pressure-operated switch comprising a casing having an encircling wall, a curved spring tube mounted in said casing having 125 an inlet for admission of pressure fluid, one end of said tube being movable in consequence of changes in the pressure of said fluid, a guide fixed in said casing, a contact piece held by said guide and constrained 130

- thereby to move in a given path, a complementary contact mounted upon said encircling wall and projecting toward the first-named contact piece, and operating means between the movable part of said spring tube and the first-named piece operative to cause the separation of the latter from the complementary contact piece when the spring tube is distorted in one direction.
- 10 5. A pressure-operated switch comprising a pressure-measuring movable actuating member, complementary switch contacts, one of which is relatively stationary and the other of which is guided to move in a prescribed path toward and away from the first one, and means supporting the first-named contact in a manner permitting it to be moved with the second-named contact when the contacts become fused together.
- 20 6. A pressure-operated switch comprising a pressure-measuring movable actuating member, complementary switch contacts, one of which is relatively stationary and the other of which is guided to move in a prescribed path toward and away from the first one, means supporting the first-named contact in a manner permitting the latter to be moved with the second-named contact when the contacts become fused together, and a stationary cut-out element in position to be electrically engaged by the second-named contact in the course of continued movement thereof.
7. A switch comprising a fixed guide, a contact mounted and movable upon said guide having a lateral arm, a complementary contact in the line of movement of the first named contact toward and away from which the latter is movable, means permitting movement of said complementary contact with the other contact in case the said contacts should fuse together, and a short circuit contact arranged at the opposite side of said arm from the said complementary contact to be engaged by the latter when the first contact is withdrawn from its normal position of engagement with said complementary contact, but without separating therefrom in case of fusing.
- 50 8. A switch according to claim 7 combined with a pressure gage having a pressure measuring member and distinguished by a pin connected with and moved by said member and arranged to bear on said arm and withdraw it from the complementary contact toward the short circuiting contact.
9. In a switch of the character described, a hollow screw, a contact supported upon one end of said screw and having a shank entering the bore of the same, said contact being free, except for the after mentioned wire, to move away from the screw, and a wire connected at one end to said shank and at the other end to said screw at a distance from its connection with the shank, being formed in part as a spring yieldingly retaining said shank in the screw.
10. A device according to claim 9 distinguished by the fact that said wire passes longitudinally through the bore of the screw and is formed as a helix through part of its length, its opposite ends being connected as described to the contact and the screw respectively.
11. A temperature governed electric switch comprising two complementary contacts, having substantially coextensive, parallel contacting faces of substantial area, one of said contacts being normally stationary, but adjustable, and the other being movable away from and toward the first contact, holding means for the respective contacts constructed to permit such adjustment and movement, respectively, and also being arranged to compel the adjusting movement of the one and the movement of separation and approach of the other to take place in the same path with preservation at all times of the parallel relation of said faces, whereby separation and closing together of the contact faces occur equally at all points in any adjustment, a Bourdon tube so mounted that its free end is constrained to move in directions approximating those of said path, and means by which said tube end in the course of its movement in one direction, and at a point determined by the adjustment of the contacts, removes the movable contact from the normally stationary contact.
12. A temperature-controlled electric switch adapted to control an electrical heating circuit comprising the combination of a curved elastic member fixed at one end and free at the other end to move responsively to the effects of temperature changes, a case enclosing said member, a holder mounted in said case, a relatively movable switch contact held by said holder within the case, means on the holder constructed and arranged to limit the movement of said contact to a path approximating in direction to the path in which the free end of the elastic member moves, an arm projecting from said contact transversely to said paths, a pin in connection with the free end of said member underlying said arm in position to engage and move the same, and the contact with it, when the elastic member is moved in one direction, and a normally stationary complementary contact mounted with provision for adjustment in the same path with the relatively movable contact.
13. A pressure-operated electric switch adapted to control an electrical heating circuit comprising a Bourdon spring tube, a case in which said spring tube is contained and in which it is fixed at one end with provision for admission of fluid to said fixed end, a holder located in said case substantially within the continuation of the curve

of the spring tube, a movable switch contact held by said holder, the latter having means for compelling the movement of said contact to take place in a fixed path which extends 5 in generally the same directions in which the free end of the Bourdon tube moves, and the contact having an end contacting face of substantial area transverse to said path, a normally stationary contact mounted with 10 provision for adjustment along the said path and having an end contacting face within the case complementary in area, contour, and position to the end face of the movable contact, and projections connected 15 to the movable contact and to the Bourdon tube respectively, each crossing the path in which the other moves whereby the tube in the course of its pressure-induced movement in one direction is enabled to displace said 20 movable contact.

14. A temperature-governed electric switch

adapted to control an electrical heating circuit, comprising complementary contacts having parallel meeting faces of substantial area, a holder having a cylindrical guide portion perpendicular to said faces in which one of said contacts is fitted to slide endwise, a holder in which the other contact is mounted with rotatable screw threaded engagement on an axis substantially coinciding 25 with the axis of said guide portion, a temperature-controlled element adapted to be distorted in consequence of temperature changes, and an operating means connected with said element and movable therewith in 30 generally the same directions as the contacts, arranged to displace the first contact from the other contact at a predetermined point in the movement of said element.

In testimony whereof I have affixed my 35 signature.

ALBERT B. COBB.
